Walter Light Bodman, Inventor,
By his Attorney
Ramsay Hoguet.

UNITED STATES PATENT OFFICE.

WALTER LIGHT BODMAN, OF NEW YORK, N. Y.

CARTON OR CONTAINER.

Application filed November 4, 1926. Serial No. 146,254.

My invention relates to improvements in containers, usually in the form of a carton. My improved container is particularly adapted as an insulating and bracing element to be used between walls to insulate them from each other against heat transmission and radiation, and brace them. Containers of this general description have been found to be of great advantage for the purpose stated, as they are light and strong, and can be made good heat insulators. In producing containers of this kind, however, there are certain attributes which must obtain. The container must be cheap or it cannot be economically used; it must be light to prevent adding undue weight to the material to which it is applied; it must be moisture proof; it must be a good insulator; and from the fact that these containers are sometimes exhausted and then filled with a gas; or sometimes used to contain dead air, it follows that such a container must be air and gas tight.

To enable the container to meet the above conditions, it must also be provided with a valve, but the valve should be self closing and must be exceedingly simple and cheap or otherwise its expense would prevent its use, and obviously the use of the container. My invention is intended to fulfill the above conditions. This will be better understood from the following description.

Reference is to be had to the accompanying drawings forming a part of this specification, in which similar reference characters indicate corresponding parts in all the views.

Figure 1 is an end view of the container showing the valve arrangement.

Figure 2 is a longitudinal section of the container, and

Figure 3 is a broken side elevation.

The body of the container can be of any desired shape, but it is usually cylindrical as it is easier to make it in this form, and moreover such a shape gives it the greatest strength for a given weight. The body has an inner wall 10 which can be of paper, wood pulp, or other suitable inexpensive material, a middle layer 11 of metal foil, preferably lead foil, and an outer layer 12 of paper or other cheap poor conducting material. These parts 10, 11 and 12 can be pasted or otherwise fastened together to make a complete composite body.

The container is provided with a closing cap 13 at one end, and a similar cap 13' at the

other. These caps are in form not novel, having flanges 14 which fit over the container body, but they are made like the body already described, each having an inner layer 15 of paper or suitable material, an intermediate layer 16 of metal foil, and an outer layer 17 of non-metallic material, as for example paper. The inner layer 15 of each cap is of such a size as to overlie the end portions of the metal layer 11 of the body, thus making better insulation as the metal parts of the body and caps will be out of contact. It will be noted that when the carton is thus made it can be thin, light, and strong, as the caps give it additional strength, and it will be further observed that it will be a poor conductor of heat, and will be impervious to moisture, air, or other gas.

To provide for exhausting or filling a container, a valve must be provided, and to this end the container is perforated at one end as shown at 19, although the perforation might be located at any desired point. This perforation is closed on one side, preferably the inner side, by a valve 20 in the form of an elastic diaphragm, rubber being suitable. The valve is secured to the inner wall so as to close the opening 19, and it is slotted as shown at 21 to permit a capillary tube 22 to be pushed through the slit for the purpose of exhausting the container or of inserting a gas or other medium. The tube 22 can be readily pushed through the valve 20, and when it is withdrawn, the slit 19 closes, and because of the elastic nature of the valve, the slit will close with sufficient tightness to prevent noticeable leakage. To insure an hermetical seal, however, a seal 23 of paper or other material can be pasted over the outside of the hole 19 as illustrated in Figure 3.

Thus it will be seen that I have produced a very cheap, strong, light, simple container, fulfilling the requirements above specified, and particularly well adapted for the uses noted, and for many other uses which I have not mentioned.

I claim:

1. As an improved article of manufacture, a gas and water tight container having a laminated body and an inner lamination of metal foil, and laminated caps closing over the ends of the body, the caps also being of laminated structure containing a layer of foil disposed so that the foil of the body and that of the caps are out of contact.

2. As an improved article of manufacture, a container or carton of poor heat conductivity having a metallic layer between its outer and inner walls with the metallic layer of the body out of contact with the metallic layers of the end portions.

3. As an improved article of manufacture, a container or carton having inner and outer non-metallic poor heat conducting walls, and 10 a metallic layer between said walls with the metallic layer of the body out of contact with the metallic layers of the end portions.

4. As an improved article of manufacture, a container having inner and outer non-metallic walls of poor heat conductivity, and 15 an intermediate layer of metal foil between the walls with the metallic layer of the body out

of contact with the metallic layers of the end portions.

5. As an improved article of manufacture, 20 a container or carton having a body with inner and outer walls of poor conductivity, a metallic layer between the said walls, and caps fitting over the ends of the body, said caps being of poor conductivity and having 25 an internal layer of metal, and with the inner wall of each cap overlying the metal portion of the body of the carton with the metallic layer of the body out of contact with the metallic layers of the end portions. 30

In testimony whereof, I have signed my name to this specification this 26 day of October, 1926.

WALTER LIGHT BODMAN.
